Primary Examiner — Rhea Shields

(57) **CLAIM**

The ornamental design for bed post, as shown and described.

DESCRIPTION

1. Bed post

1.1 : Perspective

1.2 : Front

1.3 : Left

1.4 : Back

1.5 : Right

1.6 : Top

1.7 : Bottom

Fig. 1.1 is a perspective view of the bed post; fig. 1.2 is a front view of the bed post; fig. 1.3 is a left side view of the bed post; fig. 1.4 is a back view of the bed post; fig. 1.5 is a right side view of the bed post; fig. 1.6 is a top view of the bed post; fig. 1.7 is a bottom view of the bed post.
